UNITED STATES PATENT OFFICE

JOHN F. O'CONNOR, OF CHICAGO, ILLINOIS, ASSIGNOR TO W. H. MINER, INC., OF CHICAGO, ILLINOIS, A CORPORATION OF DELAWARE

RAILWAY DRAFT RIGGING

Application filed January 28, 1929. Serial No. 335,479.

This invention relates to improvements in railway draft riggings.

One object of the invention is to provide a railway draft rigging including coupler means, cooperating shock absorber means and a front follower element having an extension for supporting the coupler shank closely adjacent the head of the coupler to maintain the horizontal alignment thereof with the parts 5 of the draft rigging, together with outer stop means for limiting the outward movement of the follower, including members fixed to the draft sills.

Another object of the invention is to provide a railway draft rigging including coupler means having longer travel in buff than in draft, shock absorbing means cooperating with the coupler means, an outer follower for the shock absorbing means having a supporting member for the coupler shank forming 15 a part of said follower, the supporting portion sustaining the coupler shank closely adjacent the head thereof, and front stop means for limiting outward movement of 20 the follower including key elements engaging the follower and also serving to guide the inner end of the coupler shank and supporting the same to prevent rocking and drooping of the coupler head.

A still further object of the invention is to provide a railway draft rigging including a coupler having relatively longer travel in buff than in draft, shock absorbing means cooperating with the coupler including two 25 separate shock absorbing mechanisms, one of which is actuated through the coupler and the other shock absorbing mechanism interposed therebetween, to provide relatively longer travel of the coupler in buff, a yoke connecting the coupler and one of said shock absorbing mechanisms, whereby said shock absorbing mechanisms is actuated only on outward movement of the coupler to provide the shorter 30 travel of the latter in draft, a front or outer follower cooperating with said last named shock absorbing mechanism, the follower having a supporting member for the coupler formed as a part of the same, the supporting 45 member engaging the coupler shank closely

adjacent the head and the maximum extension of the coupler with respect to said supporting member being not greater than the amount of movement of the coupler in draft, thus protecting trainmen against injury by 55 being caught between the coupler head and the adjacent parts of the car, and outer stop means for the follower including members extending across the follower and anchored to the draft sills. 60

Other and further objects of the invention will more clearly appear from the description and claims hereinafter following.

In the drawing, forming a part of the specification, Figure 1 is a longitudinal, vertical sectional view of a portion of the under-frame structure at one end of the railway car, illustrating my improvements in connection therewith. Figure 2 is a horizontal, longitudinal sectional view, corresponding substantially to the line 2-2 of Figure 1. And Figure 3 is a vertical, transverse sectional view, corresponding substantially to the line 3-3 of Figure 1. 65

In said drawing, 10-10 indicate channel-shaped center sills which extend through the usual body bolster 11 and are secured thereto. A combined body bolster filler and rear stop casting 12 is interposed between the sills, the same being of well known design and having forwardly extending side arms 13-13 and a buffing face 14. The casting 12 is provided with the usual center pin receiving opening, as shown in the drawing. The underframe structure of the car is provided with the usual channel-shaped end sill 15 having an opening 16 adapted to accommodate the coupler shank. The bottom wall of the opening is defined by a carry iron 17 secured to the bottom flange of the end sill 15, a wear plate 18 being supported on the carry iron. 70

In carrying out my invention, I provide the sills 10 with cheek plates 19-19 having longitudinally disposed reinforced coupler key receiving guide slots 20-20. The cheek plates are provided with angularly extended flange sections 21-21 at the forward ends thereof, which are riveted to the vertical web of the end sill 15. Each cheek plate is ex- 75 80 85 90 95 100

tended above and below the slot 20, as clearly shown in Figure 3, the top and bottom portions being provided with key receiving openings 22-22 which are reinforced, as shown, 5 the web of the corresponding center sill being provided with openings adapted to receive the reinforcements about said key receiving openings.

In connection with my improved railway 10 draft rigging, I employ the usual coupler, which is designated by 23. The coupler comprises the usual shank portion which is disposed within the opening 16 and a head at the outer end, the head being only partly 15 shown in the drawing. The coupler is connected to a horizontally disposed U-shaped yoke 24 by means of a transverse coupler key 25 extending through an opening in the coupler shank and aligned openings 26-26 20 in the side members of the yoke. A shock absorbing mechanism of the friction type is disposed within the yoke, the same comprising the usual friction shell 27, cooperating friction shoes 28-28 and wedge member 29. 25 As will be understood, the friction shell contains the usual shock absorbing springs which oppose inward movement of the shoes. The inner end portion of the shell bears directly 30 on the transverse cross member at the inner end of the yoke. A combined follower and supporting sleeve member 40 accommodates the shank portion of the coupler 23 and also the front ends of the arms of the yoke 24. The sleeve portion of this member is of sub- 35 stantially rectangular cross section and has spaced top and bottom walls 30-30 extending the entire length of the sleeve, spaced relatively short side walls 31-31 at the forward end of the sleeve, and a transverse vertical 40 rear end wall 32, of relatively great thickness, forming the front or outer follower member cooperating with the friction shock absorbing mechanism. As shown in Figure 2, the wall 32 is cut away at opposite sides so as to ac- 45 commodate the side members of the yoke 24. The front end of the side members of the yoke are spaced such a distance from the inner ends of the side walls 31 of the sleeve so that a certain amount of relative movement 50 is permitted between these parts. As shown, the inner faces of the side walls 31 converge outwardly to correspond with the shape of the shank of the coupler and are spaced therefrom so as to permit a certain amount of 55 lateral swinging movement of the coupler.

The front end of the sleeve terminates closely adjacent the head of the coupler and the bottom wall 30 is provided with an up-standing flange 33 at the forward end thereof, on which the coupler shank is supported. The top wall is provided with a similar flange but the latter is spaced from the top face of the coupler shank, as shown in Figure 1. The inner end of the coupler shank bears directly 60 on the follower member 32 and the

latter has a wedge block 29 of the friction shock absorbing mechanism bearing thereon.

Outward movement of the front follower 65 32 is limited by stop means comprising top and bottom fixed keys 34-34 extending through the sides of the sleeve section and having their opposite ends disposed in the key receiving openings 22 of the cheek plates. The keys may be held against removal by any 70 well known means, cotter pins being shown as employed in the present instance. The keys 34 are spaced apart such a distance as to embrace and guide the inner end of the coupler shank, thereby preventing tilting or 75 rocking movement of the coupler on the supporting flange 33. The inner edges of the keys 34 are normally engaged by the follower 32, thus positively limiting the outward movement of the same. The sleeve portion 80 of the combined follower and supporting member for the coupler shank is directly supported on the wear plate 18 associated with the carry iron 17.

A spring shock absorbing mechanism is interposed between the shell of the friction 85 shock absorbing means and the stop face 14 of the filler casting 12.

As shown, the spring shock absorbing mechanism comprises a rear follower block 90 35 forming a spring cage, the same being provided with top and bottom spring receiving pockets open at the front end and closed at the rear end by a transverse wall 36. The resilient member of this shock absorbing means preferably comprises upper and lower 95 spring members 37-37, each comprising inner and outer coils. The spring members 37 bear, at their front ends, on a spring follower block 38 which is transversely recessed on the forward side, as indicated 100 on 39, to accommodate the transverse end member of the yoke 24. The opening 39 is of such a size as to provide clearance between the end face of the cross member of the yoke and the inner wall of the opening, so 105 that the follower 38 bears directly on the rear end wall of the friction shell 27. The follower block 35 is preferably of the same length as the forwardly extending arms 13 110 of the filler casting, so that the rearward movement of the follower block 38 will be arrested by engagement with both the block 35 and the front ends of the stop arms 13.

As shown in the drawing, a slight clearance is provided between the front edge of 115 the coupler key and the front wall of the key receiving opening in the coupler shank, and the rear edge of the key is spaced an appreciable distance from the rear end walls of the slots 26 of the yoke arms. It will be evident 120 that the coupler shank is thus displaceable inwardly with respect to the key to a limited extent before the key will be forced rearwardly with the coupler, movement of the 125 coupler inwardly of the yoke being thus per-

mitted to an extent in excess of the inward movement of the key in the slots 26, thereby permitting full compression of the friction shock absorbing mechanism and engagement 5 of the follower member 32 with the front end of the friction shell 27 without the key actually engaging the inner end walls of the slots in the side arms of the yoke. The amount of relative movement between the 10 yoke and the sleeve member, by spacing the front ends of the arms of the yoke from the inner ends of the side walls 31 of the sleeve, is in excess of the compression stroke of the spring shock absorbing mechanism, thereby 15 permitting engagement of the follower block 38 with the block 35 and stop arms 13 before the front ends of the yoke arms will be engaged by the side walls of the sleeve member.

The friction shell 27 and the follower block 20 or spring cage 35 are supported from the draft or center sills 10 by saddle plates 59—59, three such plates being preferably employed, one of the same supporting the member 35 substantially centrally thereof, another sup- 25 porting the friction shell substantially centrally, and a third supporting the friction shell at the rear end thereof. In this connection, it is pointed out that the inner end of the combined sleeve and follower 40 is 30 supported by the upper key 34, thereby keeping the same in proper horizontal alignment.

The operation of my improved railway draft rigging, during outward or draft movement of the coupler, is as follows: The yoke 35 24 will be pulled outwardly with the coupler by means of the connecting key 25, thereby compressing the friction shock absorbing mechanism between the inner end of the yoke and the follower member 32 which is held 35 stationary by the keys 34. Compression of the friction shock absorbing mechanism is limited by engagement of the front end of the shell with the follower 32.

Upon release, the expansive action of the 45 spring resistance means within the shell will force the friction shoes and wedge block outwardly, thereby restoring the parts to the normal position shown in the drawing. During a buffering action or inward movement of the coupler, the follower member 32 will be 50 carried inwardly compressing the friction shock absorbing mechanism and at the same time forcing the follower block 38 rearwardly through the medium of the shell 27, there- 55 by compressing the springs 37 against the end wall of the follower block 35 which is held stationary by engagement with the combined filler and stop casting 12. Compression of the friction shock absorbing mechanism is 60 limited by engagement of the follower 32 with the front end of the friction shell and compression of the spring shock absorbing mechanism is limited by engagement of the follower block 38 with the front end of the 65 follower block 35 and the arms 13 of the stop

casting. It will be evident that the travel of the coupler during the action last described is greater than the travel of the same during the draft action, the travel in buff being equal to the combined compression strokes of the friction and spring shock absorbing mechanisms. Inasmuch as the follower 32 forms a part of the sleeve in which the coupler shank is housed, the coupler and follower, together with the sleeve member, will move in unison both during the inward movement of the coupler in buff and the outward movement in release after the buffering action, with the result that the coupler head will be always spaced the same distance from the front end of the sleeve during said action.

Extension of the coupler with respect to the sleeve occurs only during the draft action of the mechanism and never exceeds the amount of the compression stroke of the friction shock absorbing mechanism. Inasmuch as the compression stroke of the friction shock absorbing mechanism is that of a standard draft gear employed in present railway practice, the extension of the coupler will not exceed that generally permitted in standard railway practice, and there is therefore no danger of trainmen being injured by being caught between the coupler head and the striking face at the end of the car.

The combined front follower and sleeve also prevent drooping of the coupler head and further serve to maintain the proper alignment of the coupler shank with the remaining parts of the railway draft rigging, the front end portion of the shank being supported on the transverse flange of the sleeve while the rear end is guided between the keys 34—34 which also act as front stops for the friction shock absorbing mechanism. In addition, the sleeve is supported by the usual carry iron at the forward end and by the upper key 34 at the rear end.

While I have herein shown and described what I consider the preferred manner of carrying out my invention, the same is merely illustrative and I contemplate all changes and modifications which come within the scope of the claims appended hereto.

I claim:

1. In a railway draft rigging, the combination with center sills; of a coupler; shock absorbing means; yoke means connecting the coupler and shock absorbing means; a movable supporting member for the coupler shank, said supporting member supporting the coupler shank forwardly of the connection thereof with the yoke, in all operative positions of the coupler; an outer follower cooperating with the shock absorbing means, said follower being rigid with said supporting member; and outer stop means for said follower fixed to the center sills.

2. In a railway draft rigging, the combination with spaced center sills; of a coupler;

shock absorbing means; yoke means connecting the coupler and shock absorbing means; a movable supporting sleeve for the coupler shank; an outer follower cooperating with the shock absorbing means, said outer follower being rigid with said sleeve; and outer stop means fixed to the sills extending through said sleeve and cooperating with said follower to limit the outward movement thereof.

3. In a railway draft rigging, the combination with spaced center sills; of a carry iron secured to the sills adjacent the outer ends thereof; a coupler; shock absorbing means; yoke means connected to the coupler and enclosing said shock absorbing means; an inner stop casting between the sills; a second shock absorbing means interposed between the yoke and stop casting; outer stop means fixed to the sills; an outer follower cooperating with said first named shock absorbing means, said outer follower having its outward movement limited by said outer stop means; and a supporting sleeve into which the coupler shank extends, said sleeve being slidably supported by the carry iron outwardly of the connection of the coupler with the yoke and overlapping said carry iron in all operative positions thereof and forming a part of the outer follower, said sleeve engaging and supporting the coupler shank outwardly of the connection of said shank with the yoke.

4. In a railway draft rigging, the combination with spaced center sills; of a coupler; shock absorbing mechanism between said sills; a back stop casting; a second shock absorbing mechanism interposed between the back stop and the first shock absorbing mechanism and actuated through the latter; a yoke connecting the first named shock absorbing mechanism and coupler; a follower cooperating with said first named shock absorbing mechanism, said follower having an extended sleeve member receiving the coupler shank and supporting the same closely adjacent the head of the coupler; and transversely disposed keys anchored to the sills and limiting outward movement of said follower.

5. In a draft rigging for railway cars, the combination with draft sills and a coupler; of a yoke enclosing a shock absorbing means, said yoke and coupler having a lost motion connection; a supporting member for the coupler shank, having a front follower member forming a part thereof, said supporting member engaging the under side of the coupler shank outwardly of the connection thereof with the yoke and retaining bars anchored to the sills, disposed above and below the coupler shank at the inner end thereof and closely embracing the shank.

6. In a draft rigging for railway cars, the combination with center sills and a coupler;

of a horizontal yoke including spaced side members and a transverse inner end member; a key connecting the side members of the yoke to the coupler shank; a front follower provided with a forwardly extending supporting member engaging beneath the coupler shank adjacent the coupler head, said supporting member being sustained by the usual carry iron of the railway draft rigging, said member supporting the shank of the coupler adjacent the coupler head; means anchored to the center sills cooperating with the inner end of the coupler shank to prevent vertical displacement thereof, said means forming front stop members for limiting outward movement of the follower; and shock absorbing means within the yoke cooperating with said follower.

7. In a railway draft rigging the combination with spaced center sills of coupler means adapted to receive the actuating force in buff and in draft; a shock absorbing means cooperating with said coupler means and actuated thereby in buff; a second shock absorbing means actuated through movement of said first shock absorbing means in buff; connecting means between said coupler means and first shock absorbing means for effecting compression thereof in draft, independent of the second named shock absorbing means; follower means cooperating with said first named shock absorbing means, said follower means having a sleeve portion forming a part thereof, said sleeve receiving the coupler shank, the outer end portion of said sleeve supporting said coupler shank; and means secured to said draft sills at the outer ends thereof for slidably supporting said sleeve portion of the follower, said sleeve portion overlapping said supporting means in all operative positions of the sleeve.

8. In a railway draft rigging, including center sills and a rear stop member, the combination with a coupler element adapted to receive the actuating force in both buff and draft; of friction shock absorbing means; spring shock absorbing means interposed between the rear stop and the friction shock absorbing means, said spring shock absorbing means being compressed in buff through the interposed friction shock absorbing means, the compression stroke of each of said means being limited, whereby the total compression stroke in buff is equal to the combined compression stroke of said two means; yoke means for transmitting the actuating force from said coupler element to said friction shock absorbing means only during draft, whereby the draft stroke is limited to the permissible compression stroke of said mechanism only; a sleeve receiving and supporting the coupler shank adjacent the coupler head, said sleeve having a front follower member formed as a part thereof and cooperating with the friction shock absorbing

means; and outer stop means for limiting the outward movement of said sleeve.

9. In a draft rigging for a railway car, the combination with a carry iron at the end of the car; of a coupler; a shock absorbing means; yoke means connecting the coupler and shock absorbing means; a movable supporting slide for the coupler shank supported on the carry iron and normally extending outwardly beyond said carry iron, said slide engaging the coupler shank in supporting relation at a point outwardly of the connection thereof with the yoke; an outer follower for the shock absorbing means, said outer follower being formed rigid with said slide; and outer stop means cooperating with said follower.

10. In a railway draft rigging including center sills and a carry iron at the outer ends 20 of the sills, the combination with a coupler element adapted to receive the actuating force in both buff and draft; of shock absorbing means; and an outer follower cooperating with the shock absorbing means, said 25 follower having an integral sleeve portion guided on the carry iron and receiving the coupler shank, the outer end section of said sleeve portion normally engaging the coupler shank in supporting relation outwardly 30 of the carry iron member, said sleeve portion overlapping the carry iron in all operative positions of the sleeve portion.

In witness that I claim the foregoing I have hereunto subscribed my name this 24th 35 day of January 1929.

JOHN F. O'CONNOR.
